PLANTER BASE FOR YARD LIGHT POLE

Herman E. Erickson, 2325 W. 2nd St.,
Duluth, Minn. 55806

Filed May 15, 1970, Ser. No. 33,001

Term of patent 14 years

Int. Cl. D11—02

U.S. Cl. D35—3

FIG. 2.

FIG. 1.

FIG. 3.

FIG. 4.

FIG. 1 is a top plan view of a planter base for a yard light pole embodying my new design.

FIG. 2 is a bottom plan view thereof.

FIG. 3 is an enlarged side elevational view, all sides being identical.

FIG. 4 is an enlarged sectional view on the line 4—4 of FIG. 1.

I claim:

The ornamental design for a planter base for yard light pole, as shown.
